Patented Jan. 19, 1909.

UNITED STATES PATENT OFFICE.

SIRENOUS W. WIGNER, OF DOUGLAS, ARIZONA TERRITORY.

WASHBOARD.

No. 910,335.

Specification of Letters Patent.

Patented Jan. 19, 1909.

Application filed July 22, 1908. Serial No. 444,736.

To all whom it may concern:

Be it known that I, SIRENOUS W. WIGNER, a citizen of the United States, residing at Douglas, county of Cochise, and Territory of Arizona, have invented a certain new and useful Improvement in Washboards, of which the following is a specification.

My invention relates to new and useful improvements in washboards, and has for its object to provide an exceedingly simple and effective device of this character whereby the washing surface of the board will give when pressed against by the user.

With these ends in view, this invention consists in the details of construction and combination of elements hereinafter set forth and then specifically designated by the claim.

In order that those skilled in the art to which this invention appertains may understand how to make and use the same, I will describe its construction in detail, referring by letter to the accompanying drawing forming a part of this specification, in which—

Figure 1 is a front elevation of my improved washboard. Fig. 2, a longitudinal sectional view thereof, and, Fig. 3, a back view of the lower portion of the back, clearly showing the position of the spring.

In carrying out my invention as here embodied, A represents the sides of the washboard, and may be of any desired shape or size, and across the top of these is fastened the top board B, then on the back is secured the backboard C, so that it comes in contact with the top board B.

Secured between the sides A in proximity to the upper ends, and extending horizontally is the rest D; this rest may be of wood or metal, either of which is desirable for this purpose, that is it acts as a shelf on which the soap may be laid when the person using the board does not desire to use the soap.

E indicates a brace secured between the sides A in proximity to their lower ends.

F represents the washboard proper or washing surface to which is secured the back G, and these are pivoted between the upper ends of the sides A by some suitable means, such as screws or nails H.

To the lower end of the back G are fastened the flat metallic springs I, parallel with the sides and the flat metallic spring J running parallel with the bottom of the back, and these springs are adapted to rest against the brace E when the washboard proper is in position.

In practice while a person is using the board, when they bear down upon the washboard proper it will give to a certain extent because of the spring, and this will make the washing easier as it will absorb a great deal of the shock, which is caused when using the board in which the washing surface is permanently secured to the sides.

Of course I do not wish to be limited to the exact details of construction here shown as these may be varied within certain limits without departing from the spirit of my invention.

Having thus fully described my invention what I claim as new and useful is—

In a wash-board, the combination of two sides, means for holding the tops of said sides always in their same relative position, a brace fastened between said sides in proximity to their lower ends which with the top board will keep the sides parallel, a washboard proper pivotally secured between said sides in proximity to their upper ends, flat springs running parallel with the sides of the board secured to the back of the wash-board proper in proximity to its lower end adapted to rest against the brace, and a flat spring secured by its center portion to the lower end of the wash-board proper, said spring running parallel with the lower edge of the wash-board proper adapted to rest upon the upper surface of the brace, as shown and described.

In testimony whereof, I have hereunto affixed my signature in the presence of two subscribing witnesses.

SIRENOUS W. WIGNER.

Witnesses:

CHARLES MOSES,
ROBT. HART,
